BEVERAGE GLASS OR SIMILAR ARTICLE

Walter B. Achenbach, Toledo, Ohio, assignor to
Owens-Illinois, Inc.

Filed Jan. 5, 1973, Ser. No. 321,244

Term of patent 14 years

Int. Cl. D7—01

U.S. Cl. D7—13

FIG. 2

FIG. 1

FIG. 4

FIG. 3

MAR 12 1974

FIG.5

FIG.6

FIG.7

FIG. 1 is an elevational view of a beverage glass or similar article embodying my new and ornamental design in the size and proportions of a water tumbler;

FIG. 2 is a top plan view thereof;

FIG. 3 is a bottom plan view thereof;

FIG. 4 is a central sectional view thereof, as viewed along and in the direction of the sectional plane 4-4 designated in FIG. 3;

FIG. 5 is an elevational view of a beverage glass or similar article embodying my new and ornamental design in the size and proportions of a juice glass;

FIG. 6 is an elevational view of a beverage glass or similar article embodying my new and ornamental design in the size and proportions of a cocktail glass; and

FIG. 7 is an elevational view of a beverage glass or similar article embodying my new and ornamental design in the size and proportions of a highball glass.

I claim:

The ornamental design for a beverage glass, or similar article, as shown and described.
